(57) **CLAIM**

What is claimed is the ornamental design for a mobile device charger, as shown and described.

DESCRIPTION

FIG. 1 is a top perspective view of a mobile device charger.
FIG. 2 is a top plan view thereof.

FIG. 3 is a front side elevational view thereof; and,
FIG. 4 is a right side elevational view thereof, the left side
elevational view being identical thereto.

Any features shown in dotted, dashed, and/or broken lines do
not form part of the claimed design. Any surface shading is
used solely to show the character and/or contour of the sur-
face represented.
